UNITED STATES PATENT OFFICE.

WILLIAM W. PECK, OF KALAMAZOO, MICHIGAN.

FOUNDRY-FLASK.

1,287,417.

Specification of Letters Patent. Patented Dec. 10, 1918.

Application filed June 10, 1918. Serial No. 239,129.

To all whom it may concern:

Be it known that I, WILLIAM W. PECK, a citizen of the United States, residing in the city and county of Kalamazoo, State of Michigan, have invented certain new and useful Improvements in Foundry-Flasks, of which the following is a specification.

This invention relates to improvements in foundry flasks.

- 10 The main object of this invention is to provide an improved metal foundry flask which is very durable, strong and rigid, and at the same time not objectionably heavy, and one which is economical to manufacture.
- 15 Further objects, and objects relating to structural details, will definitely appear from the detailed description to follow.

I accomplish the objects of my invention by the devices and means described in the 20 following specification. The invention is clearly defined and pointed out in the claims.

A structure which is a preferred embodiment of my invention is clearly illustrated in the accompanying drawing, forming a 25 part of this specification, in which:

Figure I is a perspective view of my improved flask assembled.

Fig. II is a vertical section on a line corresponding to line 2—2 of Fig. I.

30 Fig. III is an enlarged detail section through one of the corners.

Fig. IV is a section similar to Fig. III before the wall plates are united at the corners.

35 Fig. V is a detail section similar to that of Fig. IV showing another form of fillet.

Fig. VI is a detail section similar to that of Fig. III, showing the corner after welding, with the fillet of Fig. V.

40 Fig. VII is a detail section of a corner prior to welding, without a fillet.

Fig. VIII is a detail section of the corner without the fillet, after welding.

In the drawing, similar reference characters refer to similar parts throughout the several views:

Referring to the drawing, the flask members 1 and 2 are provided with the usual 50 guide members 3 and 4 respectively. As these form on part of my present invention they are not further illustrated or described in further detail herein.

The walls of my improved flask members are formed of plates 5 of pressed steel. The 55 plates preferably have longitudinal corrugations 6 pressed therein and inturned flanges 7 at their top and bottom edges also pressed therein, the plates being preferably hot-pressed.

gations 6 pressed therein and inturned flanges 7 at their top and bottom edges also pressed therein, the plates being preferably hot-pressed.

The corners of the plates are brought together, preferably with fillets 8 therein, and are integrally united by fusing welds inside and out, the welds being preferably acetylene welds, which provides substantially unitary corners, and thus, in effect, an integral structure.

The flanges are mitered together as shown in Fig. VII and are also united by welding. The corners are very strong and rigid, the advantages of which will be understood by those skilled in the art.

In Figs. III and IV triangular fillets are employed.

In Figs. V and VI square fillets are employed.

In Figs. VII and VIII no fillets are employed.

It is found quite satisfactory in flasks designed for many uses, particularly for smaller flasks and the lighter classes of work to omit the fillets.

My improved flask is very strong and rigid, being capable and well adapted to withstand rough usage, such as being thrown about in the foundry or in transportation, without being sprung or distorted and also well adapted to withstand the ramming strains, and this without being unduly or excessively heavy. As it is necessary in practical use that these flask members be interchangeable the great advantage of, and necessity for their retaining their exact form will be apparent.

Having thus described my invention, what I claim as new and desire to secure by Letters Patent, is:

1. A foundry flask, the side walls of which are plates of pressed steel having longitudinal corrugations and inwardly projecting top and bottom flanges pressed therein, there being metal fillets in the corners, said wall plates and their flanges and said fillets being united throughout at the corners of the flask by fusing welds inside and out providing an integral structure.

2. A foundry flask, the side walls of which are plates of pressed steel having longitudinal corrugations and inwardly projecting top and bottom flanges pressed therein, the top and bottom flanges being extended to

- the corners, the ends of the corrugations being adjacent to but terminating in a spaced relation to the corners, said wall plates and their flanges being united throughout at the corners of the flask by fusing welds inside and out providing an integral structure.
3. A foundry flask, the side walls of which are plates of pressed steel having inwardly projecting top and bottom flanges pressed 10 therein, there being metal fillets in the corners, said wall plates and their flanges and said fillets being united throughout at the corners of the flask by fusing welds inside and out providing an integral structure.
4. A foundry flask, the side walls of which are plates of steel, there being metal fillets in the corners, said wall plates and said fillets being united throughout at the corners 15

of the flask by fusing welds inside and out providing an integral structure.

5. A foundry flask, the side walls of which are plates of pressed metal having longitudinal corrugations, said wall plates being united throughout at the corners of the flask by fusing welds providing an integral structure, the ends of the corrugations being adjacent to but terminating in a spaced relation to the welds. 20 25

In witness whereof, I have hereunto set my hand and seal in the presence of two 30 witnesses.

WILLIAM W. PECK. [L. S.]
